UNITED STATES PATENT OFFICE.

WILLIAM H. MINER, OF CHAZY, NEW YORK.

DRAFT-RIGGING FOR RAILWAY-CARS.

1,361,478.

Specification of Letters Patent. Patented Dec. 7, 1920.

Application filed November 15, 1915. Serial No. 61,453.

To all whom it may concern:

Be it known that I, WILLIAM H. MINER, a citizen of the United States, residing at Chazy, in the county of Clinton and State of New York, having invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of efficient operation.

In the drawings forming a part of this specification, Figure 1 is a side elevation partly in vertical longitudinal section of a draft rigging embodying my invention. Fig. 2 is a plan view partly in horizontal section upon line 2—2 of Fig. 1. Fig. 3 is a cross section taken on line 3—3 of Fig. 1. Fig. 4 is a cross section taken on line 4—4 of Fig. 1. Fig. 5 is a perspective view of the front follower. Fig. 6 is a perspective view of a draft gear supporting cradle. Fig. 7 is a side elevation partly in vertical longitudinal section of a modification. Fig. 8 is a plan view partly in horizontal section of the same modification.

Referring to the drawings, the numerals 9—9 indicate draft members or parts of the car frame to which the draft rigging is applied, 10 a draft gear mounted between the draft members, 11 a draft yoke shown in horizontal position with its arms 12—12 passing on either side of the draft gear. The arms 12—12 are provided with the transverse slots 13—13 at their forward ends for the passage of the coupler key 14 which extends through the slots 15—15 in the draft members and through the slot 16 in the draw bar 17. The slots 13—13 in the draft yoke are rearwardly extended to permit the sliding of the key therein on rearward movement of the draw bar, and the slots 15—15 in the draft members are of sufficient length to permit the reciprocating movement of the key 14 therein on the forward and rearward movement of the draw bar. The front stop members are shown at the numerals 19—19, the same being oppositely arranged between the draft members 9 and each being appropriately secured to its adjacent draft member preferably by the rivets 20—20. Each of the stop mem-

bers is provided with a longitudinal groove 21 for the passage of a limb of the draft yoke, the said limbs being adapted to slide therein on movement of the yoke. A rear stop member 22 is secured between the draft members 9 preferably by the rivets 23—23, and is so positioned that when the parts of the draft rigging are in normal position as illustrated in Fig. 2 of the drawings, the rear connecting member 123 of the draft yoke 11 is adjacent the front face 24 of the said rear stop 22. The front follower 25 comprises a block 26 provided at its rear end with a preferably integral plate 27, the forward face 28 of the same being adapted to engage against the shoulders 29 of the front stop members 19. The block 26 is provided with means for entering the grooves 21 in the front stop members, the means illustrated herein being the lateral upper and lower flanges 30 and 31, respectively. These lateral extensions from the block 26 enter the grooves 21 of the front stop members 19 adjacent the limbs 12 of the yoke 11 and are adapted to ride therein on longitudinal movement of the front follower. Thus the front follower is supported by the front stop members through the medium of said lateral extensions upon the follower which enter the grooves 21 in the front stop members. The draft gear 10 illustrated in the drawings comprises a shell 32 having springs 33 therein which act in conjunction with the friction compression resisting elements including the friction shoes 34 and the spreading member or wedge 35. The wedge 35 is engaged by the rear face 36 of the front follower. A tie plate 37 arranged transversely of the draft members 9 is secured near its ends to said draft members preferably by the bolts 38—38, and serves to support the draft gear supporting cradle 40, which comprises a plate 41 provided at its ends with the up-turned flanges 42—42 which appropriately engage the draft gear, and is provided at its sides with the up-turned flanges 43 which are adapted to engage the sides of the draft gear. The said flanges are of a suitable height to be engaged along their upper edges 44 by the limbs 12 of the draft yoke 11. Thus the draft yoke is supported at its forward end by the coupler key 14, passes through the grooves 21 in the front stop members, and is supported near its rear end by the flanges 43 of the draft gear supporting cradle 40.

The draft gear supporting cradle in the particular form of my invention shown in the drawings, and particularly illustrated in Fig. 6 thereof, fits about portions of the draft gear so that the same moves simultaneously therewith.

It will thus be seen that on rearward movement of the draw bar the yoke 11 remains stationary with its rear connecting member 123 against the rear stop 22; the key 14 slides rearwardly in the slots 13-13 in the limbs of the yoke and in the slots 15 in the draft members, which slots in the drawings also extend through the forwardly extended portions 46 of the front stop members 19; the butt 47 of the draw bar 17 engages against the front face of the front follower, forcing the same rearwardly, its rearward movement being resisted by the compression resisting elements of the draft gear, the draft gear being held against rearward movement by the rear stop member.

On forward movement of the draw bar, the key 14 engages the forward edges of the slots 13 in the draft yoke 11, drawing the yoke forward, which yoke in turn draws forward the draft gear, the draft gear being stopped at its forward end by the front follower, the faces 28 of which engage against the stop shoulders 29 of the front stop members 19. The space between the rear stop member and the shoulders 29 of the front stop members 19 between the draft members 9 is commonly known as a draft gear pocket, or that space within which the draft gear of the draft rigging is received. The grooves in the stop members 19 extend beyond and are outside of this pocket in the specific embodiment of my invention illustrated in the drawings.

In the modifications illustrated in Figs. 7 and 8, the numerals 50-50 indicate the draft members, 52 the front stop members provided with longitudinal grooves 53 with which are received the lateral flanges 54-54 of the front follower 55, the front follower being provided with the stop shoulders 56 which are adapted to engage against the stop shoulders 57 of the front stop members. The front stop members also receive in the said grooves the limbs 58-58 of the draft yoke 59. The said yoke at its forward ends is provided with the slots 60 for the passage of the coupler key 61 which extends through the draw bar 62 and at its ends through the slots 63-63 in the front portion of the stop members and in adjacent portions of the draft members. A draft gear 65 is mounted in the draft gear pocket 66, the said draft gear being encircled by the yoke and being stopped against rearward movement by the rear stop member 68 provided with a stop shoulder 69. A tie plate 70 is secured to the draft members 65 preferably by the bolts 71 and has mounted

thereon the draft gear supporting cradle 72 provided with the front and rear flanges 73 and the lateral upright flanges 74 which engage it to the draft gear. The said cradle slides upon the tie plate 70 and is adapted to support the draft gear within the draft gear pocket between the front and rear stop shoulders of the draft rigging.

The operation of the modified form of my invention, as illustrated in Figs. 7 and 8 of 75 the drawings, and the structure of said modification is the same as that illustrated in Figs. 1 and 2, except in the particulars now to be mentioned: The draw bar 62 is provided near its rear end with the limiting 80 stops 77 laterally extended from the butt 78 of the draw bar. On rearward movement of the draw bar the rear face 79 engages against the front face 80 of the front follower, forcing the same rearwardly until the limiting stops 77 of the draw bar engage the front stop shoulders 81-81 of the front stop members, thereby limiting the rearward movement of the draw bar and protecting the draft gear from excessive 90 draw bar shocks. The slots 63 in the draft members are longitudinally extended so that the rear ends 82-82 of the same stop the coupler key 61 simultaneously with the engagement of the limiting stop shoulders 77 95 of the draw bar with the stop shoulders 81 of the front stop members.

I claim:

1. As an article of manufacture, a follower block for railway draft riggings, said block having a follower portion proper adapted, on one side, to engage stops and, on its other side, to engage one end of a shock absorbing means, said block having also extensions on the first named side of 105 said follower portion proper and arranged perpendicular to the latter, said extensions being adapted to slide within grooves provided in stop castings.

2. In a draft rigging for railway cars, 110 stop members and a follower, the stop members being provided with grooves without the draft gear pocket, and the follower having flanges entering said grooves.

3. In a draft rigging for railway cars, 115 stop members in combination with a follower, the stop members having stop shoulders and longitudinal grooves, the follower having a face adapted to engage the shoulders and also having members entering said 120 grooves.

4. In a draft rigging for railway cars, a pair of oppositely arranged stop members, and a follower, the stop members having longitudinal grooves and stop shoulders, 125 the follower comprising a plate to engage the stop shoulders and a member extended from said plate, said members being provided with lateral extensions entering the grooves in the stop members.

5. In a draft rigging for railway cars, a pair of oppositely arranged stop members, and a follower, the stop members having longitudinal grooves and stop shoulders, the follower comprising a plate to engage the stop shoulders and a member extended from said plate, said member being provided with lateral extensions entering the grooves in the stop members, and having longitudinal 55 sliding movement therein.
6. In a draft rigging for railway cars, the combination with draft members, stop members and a yoke, of a front follower, the front stop members being provided 10 with longitudinal grooves, the yoke passing through said grooves, and the follower having lateral extensions entering said grooves.
7. In a draft rigging for railway cars, 15 the combination with draft members, front and rear stop members secured thereto, and a draft yoke, of a follower, the front stop members having grooves for the passage of the yoke, and the follower having supporting extensions slidingly mounted in said grooves.
8. In a draft rigging for railway cars, draft members, front stop members, a horizontal yoke, a follower and a draft gear, 20 the draft gear having lateral members to support the yoke, and the follower having extensions engaging with and supported by the stop members.
9. In a draft rigging for railway cars, 25 draft members, a draft gear associated therewith, a tie plate secured to the draft members, and a draft gear supporting member slidingly mounted on said tie plate.
10. In a draft rigging for railway cars, 30 draft members, front and rear stop members thereon, a draw bar, a horizontal yoke secured thereto, a draft gear within the yoke, a tie plate secured to the draft members, a draft gear supporting cradle slidingly 35 engaging the tie plate, the front stop member having grooves for the passage of the yoke, the supporting cradle having upward extensions supporting the yoke, and the front follower having lateral extensions entering 40 the grooves of the front stop members whereby said follower is supported therein.
11. In a draft rigging the combination 45 with a draft gear and a horizontal yoke, of means for supporting said yoke comprising a member movable with the draft gear and 50 extending underneath the yoke.
12. In a draft rigging for railway cars, the combination with draft members, a horizontal yoke and a draft gear having a shell, of a draft gear supporting member movable 55 with the shell and provided with extensions engaging and supporting the yoke.
13. In a draft rigging for railway cars, in combination, draft members, a draw-bar, a yoke, a key engaging the yoke to the draw-bar and passing through the draft members, 60 a draft gear within the yoke, a tie plate secured to the draft members, a draft gear supporting member mounted thereon and movable with the draft gear, said member 65 having extensions engaging the yoke, the yoke being supported by the key and said extensions.
14. In a draft rigging for railway cars, draft members, stop members, a draw-bar, 70 a yoke slidingly secured thereto, a draft gear within the yoke, a draft gear supporting member associated therewith, said member having yoke supporting extensions, said member, gear and yoke moving together on 75 forward movement of the draw-bar, and all remaining stationary on rearward movement of the draw-bar.
15. As an article of manufacture, a follower having vertical portions adapted to 80 engage stop shoulders, said follower having an extension from the front side thereof, said extension being provided with side flanges adapted to engage in guiding 85 grooves.
16. In a draft rigging, the combination with draft sills, of front stops secured thereto, a cushioning member, a horizontal yoke, and a front follower, said stops being provided with horizontally extending channels 90 and said follower having a forward extension 95 slidable within and guided by said channels, the forward ends of said yoke also sliding within said channels on the outer sides of said extensions.

In witness that I claim the foregoing I have hereunto subscribed my name this 3rd day of November, 1915.

WILLIAM H. MINER.
